(57) CLAIM

The ornamental design for a game table, as shown and described.

DESCRIPTION

FIG. 1 is a front elevational view of a game table showing our new design;

FIG. 2 is a rear elevational view thereof;

FIG. 3 is a side view, taken from the left side of FIG. 1, the right side view being a mirror image thereof;

FIG. 4 is a top plan view thereof;

FIG. 5 is a bottom plan view thereof; and,

FIG. 6 is a perspective view of our new the game table of our design.

The broken line showing a flag in FIG. 4 and in FIG. 6 is for illustrative purposes only and forms no part of our claimed design.

1 Claim, 4 Drawing Sheets
